UNITED STATES PATENT OFFICE.

WILLIAM E. COLE, OF MONTGOMERY, ALABAMA.

LUMBER-DRIER.

SPECIFICATION forming part of Letters Patent No. 340,660, dated April 27, 1886.

Application filed September 26, 1885. Serial No. 178,257. (No model.)

To all whom it may concern:

Be it known that I, WILLIAM E. COLE, a citizen of the United States, residing at Montgomery, in the county of Montgomery and State of Alabama, have invented certain new and useful Improvements in Lumber-Driers, of which the following is a specification, reference being had therein to the accompanying drawings.

10 My invention relates to lumber-driers in which hot air alone or hot air and smoke are used to evaporate the moisture contained in lumber and other substances; and the objects of my improvements are to provide a drier in which air heated by direct contact with fire or flame, in connection with air heated by indirect radiation, can be used together or separately with safety to dry inflammable material, as lumber. I attain these objects by the 15 construction illustrated in the accompanying drawings, in which—

Figure 1 is a horizontal section of a lumber-drier constructed in accordance with my invention. Fig. 2 is a longitudinal vertical section of the same. Fig. 3 is a transverse vertical section through the rear or transverse flue and side chimneys of the drier. Fig. 4 is a similar view through the center of the drier. Fig. 5 is a front view of one of the arches on 20 a larger scale.

Similar letters refer to similar parts throughout the several views.

The dimensions of the drier may vary according to the material or the length of the lumber produced in different sections of the country. The most suitable would be about eighteen feet wide by forty to seventy feet long, and any desired height.

The frame is represented at A. It can be 40 made of lumber or other suitable material, and within the bottom of said frame are a series of arches, B, preferably made of brick, extending the whole length of the drier, and communicating at their rear end with a transverse arch, B², leading into the bottom of 45 chimneys C, provided with registers D, resting either upon the top thereof, as shown in the drawings, or placed within their interior. The rear end of each arch B is also provided 50 with a large opening, b, in the top, for the fire-heated air and smoke to escape directly

into the interior of the drier, where its caloric is absorbed by the lumber or material placed therein, and finally escapes through the large flue E, passing through the ceiling F and roof 55 A² of the drier at its forward end.

To retain the heat in the arches and prevent charring of the frame and sheathing of the drier, sand or dirt d is packed around the sides and top of said arches. To transfer 60 a portion of the latent heat of this sand directly to the rear of the drier and cause it to circulate through the lumber on its way to the flue E, a series of pipes, G, are laid horizontally, or nearly so, into the sand d, and the heat 65 of the latter, in connection with the draft produced by the chimney or large flue E, causes currents of air to enter at the front end of the pipes G and escape at the rear, adjacent to the discharge-openings b of the arches B. These 70 arches are also provided with longitudinal flues B³, either made of tiles embedded in said arches, or left as horizontal openings while building the arches. The packed sand or dirt d is retained close to the ends of the arches by 75 transverse walls A³ A⁴, and the air-flues, preferably, made of terra-cotta or of tiles, pass through these walls.

Between the sand-supporting wall A⁴ and the rear wall, A⁵, of the drier are placed horizontally one or more thicknesses of wire screens, h, to effectually arrest all sparks that may have traveled the whole length of the longitudinal brick arches. These screens, being placed horizontally on a level with the 85 drier-floor, do not interfere with the passage of cars H over rails placed upon said floor.

The doors D² of the drier are preferably arranged to slide up to open them, and are counterbalanced by weights. The openings b on 90 top of the rear portion of the arches B, are controlled by sliding dampers b', either connected together and adapted to be operated from the side or disconnected and adapted to be operated separately from the rear of the 95 drier.

When yellow pine is to be dried by fire, heated air, and smoke, the dampers b' are withdrawn from over the rear openings, b, of the arches, and the registers D of the side chimneys, C, are closed. Then, the air admitted through the pipes G and B³ as well as the air

and smoke in the arches B pass upward through the horizontal screens or spark-arresters h to the drying-room and escape through the flue E.

When the drier is to be used for white pine and other lumber that smoke might slightly darken, the arch-openings b are closed by the dampers b' and the chimney-registers D are opened to carry off the smoke; but the currents of air entering the front end of the pipes 10 G and flues B³ continue to be discharged at the rear end of the drier, and the heat ascending from the brick arches and sand and dirt floor passes directly through the lumber mounted upon the cars in the chamber A' and seasons 15 it thoroughly in one or two days of time.

The flues G and B³ may be provided with doors or stoppers, to regulate the amount of air passing through them.

Having now fully described my invention, 20 I claim—

1. The combination of the chamber A', having an air-escape flue out of its ceiling over its front end, doors at both ends, and walls A³

A' at said ends, a series of arches, B, and air-pipes G, parallel with the arches and passing 25 through the walls A³ A', with the rear wall, A³, and horizontal spark-arresting screens h, extending across the chamber substantially on a level with its floor and between the walls A³ A', substantially as and for the purpose described. 30

2. The combination of the chamber A', having doors at both ends and an air-escape flue over its front end, a floor having fire-arches, and air-pipes extending parallel with said 35 arches the whole length thereof, chimneys at the rear corners, and a transverse flue leading from the fire-arches to said chimneys, substantially as and for the purpose described.

In testimony whereof I affix my signature 40 in presence of two witnesses.

WILLIAM E. COLE.
